UNITED STATES PATENT OFFICE.

OSCAR FAUSER AND FRANK P. FAUSER, OF PEORIA, ILLINOIS.

MACHINE FOR SURFACING BUTCHERS' BLOCKS.

1,286,569.

Specification of Letters Patent.

Patented Dec. 3, 1918.

Application filed July 19, 1917. Serial No. 181,505.

To all whom it may concern:

Be it known that we, OSCAR FAUSER and FRANK P. FAUSER, both citizens of the United States, residing at Peoria, in the county of Peoria and State of Illinois, have invented certain new and useful Improvements in Machines for Surfacing Butchers' Blocks, of which the following is a specification.

10 This invention has reference more particularly to a machine for resurfacing butchers' blocks, which may be transported from place to place, and set up for operation where the block is located.

15 The object of the invention is to provide a machine which is self-supporting and may be set up with the block in the interior of the frame of the machine.

20 A further object is to provide a machine for this purpose with a plurality of adjustable supports, whereby the machine may readily be adjusted relatively to the surface of the block as desired.

25 A further object is to provide a frame which is collapsible, or may be knocked down to facilitate transportation from place to place, and admission into a building and which can conveniently be set up around the block.

30 A further object is the provision of a motor which is adjustably supported over the surface of the block and provided with the resurfacing member directly connected thereto.

35 A further object is the provision of anti-friction supporting means for the parts movable in the operation of the device whereby operation of the device is facilitated.

40 The invention also has other objects and features of improvement, which will appear from the following specification taken in connection with the drawings, and which are particularly pointed out in the claims.

In the accompanying drawing, which illustrates our invention,

45 Figure 1— is a top view of the machine and the block upon which it is operating.

Fig. 2,— a side view of the machine, looking from the bottom of Fig. 1;

50 Fig. 3,— an end view of the machine looking from the right hand side of Fig. 1;

Fig. 4,— an enlarged view showing the parts substantially on a line, $a-a$, of Fig. 2;

55 Fig. 5,— an enlarged view of the adjustable supports for the frame.

1— is an ordinary butcher's block, which may be square as shown, round, or any other suitable form, as the machine is supported independently thereof. The frame of the machine is adapted to be set up around the block and consists of the two end sections, which are detachably connected, as hereafter explained. One of these end sections consists of the vertical pipe members 2, with the pipe T's 3 at the upper ends, which are connected by means of the pipes 4. The lower ends of the pipes 2 are provided with the couplings 5, which may be connected by a pipe similar to, and parallel with the pipe 4 for thoroughly bracing this frame and there are the short pipes 6 screwed into the couplings 5 in line with, and forming a continuation of pipes 2.

The opposite end section of the frame is similarly constructed, except that the top cross pipe 4^a, has the bearing bracket 7 interposed in the length thereof and the brace pipe 8 has a T interposed in the length thereof and there is a cross pipe 9 connecting the said T with an extension 10 of the bearing bracket 7, whereby the said bearing bracket is held in the proper upright position. The T's 5^a are also slightly different than the T's 5, as hereafter mentioned. The lower ends of the pipe sections 6 are provided with collars 11 which are clamped or otherwise secured on to the lower end of the said pipes, said clamps being provided with opposite pawls 12, which are connected by means of the spring 13, to bear inwardly and engage the ratchet faces of an adjustable foot member. This foot member has the flanged or disk shaped part 14, which supports the device and may be provided with the perforations indicated by dotted lines at 15, whereby the device may be secured to the floor if desired and there is a stem 16 which extends vertically from the disk 14 and is telescoped by the pipes 6 and 2 and has the annular ratchet faces 17, which are engaged by the pawls 12 to support the frame of the machine in the desired position of elevation.

For detachably connecting the end sections there are a pair of parallel angle iron rails 18, which have one flange of the angle iron laid horizontally and connected to the corresponding ends of the two sections by means of cap screws or bolts 19, which pass through the horizontal flange of the angle iron at its 110

ends and screws into the upper end of the couplings 3.

The other flange of the angle iron extends vertically and forms a track upon which is supported the frame for carrying the mechanism for resurfacing the block. A pipe brace 20 is provided at each side to connect the two end sections, said pipe at one end having a threaded connection with the coupling 5 and at the other end is merely inserted into the coupling and secured by means of the pin 21, passed therethrough. This construction, it will be observed makes it possible for the side rails 18 and braces 20 to be readily and quickly removed and the machine rendered in condition for transportation.

Mounted upon each of the rails 18 is an end plate 22, each of which has a pair of depending flanges 23, the lower ends of which are provided with a stub bolt 24, which projects under the angle iron 18, as shown in Fig. 4, and holds the frame from removal. Each of the flanges 23 has a companion flange 25 opposite and spaced therefrom between which is pivotally mounted a roller 26, which travels on the vertical flange of the angle iron 18. The two plates 22, are connected and spaced by means of the three rods 27, which are secured to the plates by means of the clamp nuts 28, and there is a screw shaft 29 journaled in, and extending between the two plates. This screw shaft 29 has at one end, a ratchet wheel 30, which may be locked by means of a reversible ratchet pawl 31, for holding the screw shaft 29 against turning, and there is a handle 32 on this shaft for imparting rotation thereto.

Mounted upon the rods 27 intermediate of the side plates 22, is a casing 33, which is adapted to inclose a motor 34, which is supported by the said casing 33 as at 35 or otherwise secured thereto, so that the shaft 36 thereof is positioned vertically and projects through and beneath the bottom of the said casing. The lower end of this shaft is adapted to have a saw 37 secured thereto, the said saw being attached to the sleeve 38, in such a manner that the underface thereof is perfectly smooth and permits the operation of the saw against the surface of the block. This sleeve is preferably attached by means of a cap screw 39 or otherwise so that it may be very readily removed or replaced.

The rods 27 which pass through the casing 37 support the said casing and permit sliding movement from end to end of the rods, and the screw shaft 29 is also inserted through the said casing and has a threaded relation with a sleeve or nut 40, which is bolted or otherwise secured to the wall of the casing. Thus it will be observed that the turning of the screw shaft 29 by its engagement with the nut 40, will cause the casing

37 and motor therein to move longitudinally 65 along the rods.

This screw shaft 29 is designed to regulate the lateral depth of the saw against the surface part of the block to be removed by advancing the motor 34 and saw 37 laterally 70 within the frame, and when it has been turned to the proper position it is locked against further turning by engagement of the pawl 31 with the ratchet wheel 30.

For moving the sawing mechanism lengthwise of the supporting frame and across the face of the block 1, there are provided the brace rods 41, which at their outer ends are attached to the plates 22, and at the inner adjacent ends are connected to a coupling 42. A screw shaft 43 which is of sufficient length to move the sawing mechanism from one end to the other of the supporting frame, is passed loosely through companion bearings 44 and 45 of bearing bracket 7, and the inner end of this screw shaft is adapted to be inserted into the coupling 42, and secured therein by means of the pin 46, whereby it may be readily assembled, and taken apart. For moving this screw shaft lengthwise to cause corresponding movement of the sawing mechanism, there is a spur gear 47, positioned intermediate of the bearings 44 and 45 and threaded internally so as to screw upon the shaft 43. 90 A gear 48 is mounted upon an arm of bracket 7 in mesh with the spur gear and provided with a handle 50, whereby it may be turned to rotate the spur gear 47 and impart longitudinal movement to the screw shaft. 95

The device is transported from place to place in a knock-down condition which makes it easier to handle and readily taken into a building, which would be difficult and sometimes impossible in its assembled form. 105 To use the machine, the end sections are set up, one on each side of the block to be resurfaced. The pipes 20 are then screwed into the coupling 5 and the other ends of these pipes are inserted in the corresponding 110 couplings 5^a, of the opposite end section, and secured therein by means of the pins 21. The angle iron rails 18 are then placed in position and attached by means of the cap screws or bolts 19. The motor carriage is 115 then mounted on the rails 18 (the stub bolts 24 having been previously removed) and the stub bolts 24 are then secured in place to hold the said motor frame on the track. The screw 43 is then inserted through the bearings 44 and 45, and intermediate spur gear 47, and the end thereof secured to the coupling 42 by means of the pin 46. The saw is then adjusted to one side of the block and the foot plates 14 are adjusted by means of 120 the ratchet pawls 12 to position the saw so that it will take off the required amount to resurface the top of the block. The saw is 125

then adjusted by means of the handle 32 to make the required lateral depth of cut, and the saw having been set in operation, the motor frame is caused to move across the 5 face of the block by turning the handle 50, which cuts a strip loose from the upper surface of the block.

These blocks are usually made of sections 10 laid up together as shown by the dotted lines at 51, in Fig. 1 and in resurfacing, the direction of cut is made to correspond to the direction of these pieces and thus the saw may be set to cut the width of one of these 15 pieces after which the pieces cut off can readily be removed. If, however, the strip cut off does not readily break loose, it may readily be broken off by striking with a hammer or may be cut off with a chisel or hatchet as no doubt will be readily understood.

After the block has been entirely resurfaced, the machine may be knocked down by reversing the steps in assembling and the machine is then ready for transportation.

It is intended and preferred that an electric motor be employed for use with this machine and a switch 52 may be provided at one side of the motor casing 33, from which the circuit wires 53 lead to any convenient source of electric power, the said wires being of sufficient length to permit the required movement of the motor in the operation of the machine.

From the foregoing it will be noted that 35 the machine is capable of use in connection with blocks of different sizes and shapes; that the frame is adapted to be knocked down for transportation and can be built up or set up around the block so that it does not 40 have to be lifted over or clamped to the block; that it is supported independently of the block and adjustable at the four corners to provide the required relation of the new 45 surface to the block and also to regulate the depth of the cut, and that the motor is directly connected to the saw, whereby the greatest efficiency may be obtained.

What we claim is:—

1. A resurfacing machine comprising a 50 frame adapted to be positioned about a meat block or the like and having a pair of upright vertically adjustable end sections one of which including an intermediate bearing bracket at its upper end, a pair of angle 55 rails detachably secured at opposite ends to the upper corners of the end sections and forming upper braces, a pair of lower braces secured at one end to one of the sections,

and means for detachably securing the other end of the lower braces to the other end section to complete the frame, a carriage detachably mounted upon the rails, means mounted on said bearing bracket and connected to the carriage for moving the latter lengthwise of the frame, a motor mounted 60 on the carriage to slide transversely of the frame, means for moving the motor on the carriage, and a cutter depending from the motor for contact with the block and resurface the same.

2. In a resurfacing machine, the combination of a frame including top rails and standards hollow at their lower ends, a carriage on the rails, means for moving the carriage over the rails, a motor movably 75 mounted on the carriage, means for moving the motor on the carriage, a cutter depending from the motor and adjustable therewith in the frame, collars mounted exteriorly on the lower ends of the standards, a 80 pair of depending opposed pawls carried on each collar, a spring connecting the lower end portions of the pawls of each collar, for urging the same toward each other, and a foot member telescoping into the lower end 85 of each standard and adapted to engage the floor at its lower end and having annular upwardly directed ratchet faces for the reception of the pawls to adjustably support the standards.

3. In a resurfacing machine, the combination of a frame including end sections and top angle rails detachably joining the sections, a carriage detachably mounted on the frame and including end plates each having 95 a pair of flanges adapted to be placed one at each side of the upstanding portions of the adjacent rail and one flange being longer than the other to project below the rail, rollers mounted between the upper ends of the 100 flanges and adapted to ride on the upper edges of the rails for supporting the carriage, stud bolts carried by the longer flanges and projecting beneath the rails for detachably holding the flanges to the rails, 105 and a motor adjustably mounted on the carriage and equipped with a cutter depending onto the frame.

In testimony whereof we affix our signatures in presence of two witnesses.
